BOTTLE STOPPER

Paul R. Schillinger, Conyngham, Pa.

Application August 7, 1940, Serial No. 351,728

1 Claim. (Cl. 215—21)

My invention consists in a new and useful improvement in bottle stoppers and is designed to provide a device for application to an ordinary beverage bottle whereby the bottle is rendered non-refillable. The particularly novel and useful features of my improved stopper are the means which I provide for attaching the device to the neck of an ordinary bottle so that removal therefrom is effectually prevented, and the provision of a plurality of radially disposed longitudinal conduits for the passage of air and liquid, to effectively break the vacuum when the valve of the device opens for emission of liquid from the bottle. These conduits are provided by the novel structure of a pair of concentric shells associated with a freely floating gravity actuated valve disc designed to permit egress of liquid from the bottle and prevent ingress of liquid thereto.

While I have illustrated in the drawings filed herewith and have hereinafter fully described one specific embodiment of my invention, it is to be distinctly understood that I do not consider my invention limited to said specific embodiment, but refer for its scope to the claim appended hereto.

In the drawings:

Fig. 1 is a vertical section of the upper portion and neck of a bottle provided with my improved stopper.

Fig. 2 is a vertical section similar to Fig. 1, showing the parts in position to allow emission of liquid from the bottle.

Fig. 3 is an enlarged horizontal section on the line 3—3 of Fig. 1.

As illustrated in the drawings, my improved stopper has a shell S designed for insertion into the neck N of the bottle B. This shell S is provided near its top with a pair of circumferential shoulders 1 and 2 forming an annular groove 3 therebetween in which is mounted a resilient gasket 4 of any suitable material adapted to effect an air-tight joint with the inner wall 5 of the neck N, when the stopper is inserted therein. I provide a cap C having a depending sleeve 6 received in the upper end of the shell S and connected therewith by any suitable fastening means, such as rivets 7. The cap C has a depending flange 8 adapted to fit snugly about the outer wall 9 of the neck N. The cap C is suitably threaded at 10 to receive thereon a threaded cover 11. The shell S is formed with a reduced lower portion 12 forming the interior annular seat 13, and at its lower end with a further reduced portion 14 forming the interior annular seat 15. Suitably mounted on the portion 14 is

5 a resilient gasket 16 of any suitable material adapted to be compressed so as to pass through the neck N and then expand to contact the inner surface 17 of the bottle B about the neck N. 10 It is to be noted that the portion 14 on which the gasket 16 is mounted has a diameter designed to provide sufficient space between the portion 14 and the inner wall 5 of the neck N, for the passage of the compressed gasket 16 therethrough. Positioned in the portion 12 of the shell S, on the seat 15, is the valve seat 18 of any suitable material. Associated with this valve seat 18 is the valve disc 19 having a lower spheroc-convex face 20 to coact with the annular concave face 21 of the seat 18. The disc 19 is provided on its upper face with an annular upstanding flange 22.

20 An inner shell S' is snugly fitted within the outer shell S, its lower end received against the seat 13. This shell S' comprises a lower tubular portion 23, a frusto-conical portion 24 and a reduced upper tubular portion 25. The lower portion 23 is provided with a plurality of longitudinal concavities 26 forming conduits between the shells S and S'. The shell S' is provided in its lower end with a frusto-conical baffle 27 mounted on the lower end of the tubular portion 23 by straps 28, thereby forming arcuate slots 29 between the outer rim of the baffle 27 and the portion 23, and a central orifice 30.

25 When the shell S' has been positioned in the shell S, seated on the seat 13, the shell S may be tapped to provide an inner boss 31 at a suitable point to prevent relative longitudinal movement 35 of shells S and S'.

From the foregoing description of the details of construction of my improved stopper, its operation and use will be obvious.

When the bottle B has been filled with the 40 liquid which is to be purveyed, my improved stopper is applied to the bottle B by inserting it in the neck N, the gasket 16 being compressed to pass in the space between the portion 14 and the wall 5. The parts are so designed and related that when the portion 14 carrying the gasket 16 passes out of the neck N into the bottle B to permit the gasket 16 to expand and contact the wall 17 to prevent removal of the stopper, the cap C is properly positioned upon the upper end of the neck N and the flange 8 engages the wall 9, thereby preventing the stopper from being forced downwardly through the neck N into the bottle B. Also it is to be noted that the flange 8, acting as a skirt about the top of neck

N, prevents prying up the stopper by inserting a wedge between the cap C and top of neck N.

When the bottle B is tilted (as illustrated in Fig. 2) the valve disc 19 is caused to move by gravity from the valve seat 18, thereby opening a passage for emission of liquid from the bottle B. It is to be noted (Fig. 2) that the disc 19 is received against the shell S' in such a way as to expose the inner ends of the conduits 26 and also the slots 28 and orifice 30, since only the edge of the flange 22 contacts the straps 29 on the end of the shell S'. This adjustment of the parts permits flow of air under atmospheric pressure, through the conduits 26 and flow of the liquid through the slots 28 and orifice 30. Thus, by the novel arrangement of the parts of my improved stopper, the vacuum, tended to be caused by the emission of the liquid from the bottle B, is broken by ingress of air through the conduits 26.

It is obvious that when the bottle B is upright (as illustrated in Fig. 1), the valve disc 19 is

seated upon the valve seat 18, forming a liquid-proof seal to effectually prevent ingress of liquid to the bottle B, whereby my improved stopper renders the ordinary bottle B non-refillable.

Having described my invention, what I claim is:

In a bottle stopper, adapted to render an ordinary bottle non-refillable, the combination of a shell adapted to be irremovably mounted in the neck of a bottle; a valve seat mounted at the lower end of said shell; a second shell fixed in said first shell and having longitudinal grooves on its outer surface to provide conduits between said shells; a baffle plate with a central orifice mounted in the bottom of said second shell by radial straps providing arcuate slots between the edge of the plate and the second shell; and a valve member disposed between said seat and said second shell, and having an upstanding peripheral flange.

20

PAUL R. SCHILLINGER.
